(57) **CLAIM**

The ornamental design for a display screen or a portion thereof with a graphical user interface, as shown and described herein.

DESCRIPTION

FIG. 1 is a front view of a display screen or portion thereof with a graphical user interface, showing my new design; FIG. 2 is a front view of a display screen or portion thereof with a graphical user interface, showing another embodiment my new design;

FIG. 3 is a front view of a display screen or portion thereof with a graphical user interface, showing another embodiment my new design; and,

FIG. 4 is a front view of a display screen or portion thereof with a graphical user interface, showing another embodiment my new design.

The dashed broken line perimeter in the drawings illustrate a display screen or portion thereof and forms no part of the claimed design.

1 Claim, 2 Drawing Sheets
